UNITED STATES PATENT OFFICE.

IRÉNÉ DEFOY, OF ST. ROCH DE QUEBEC, QUEBEC, CANADA.

AUTOMATIC GOVERNOR-VALVE.

1,152,491.

Specification of Letters Patent.

Patented Sept. 7, 1915.

Application filed June 9, 1914. Serial No. 843,941.

To all whom it may concern:

Be it known that I, IRÉNÉ DEFOY, a subject of the King of Great Britain, residing at No. 12 Laberge street, St. Roch de Quebec, Province of Quebec, Canada, have invented certain new and useful Improvements in Automatic Governor-Valves; and I do hereby declare that the following is a full, clear, and exact description of the invention, such as will enable others skilled in the art to which it appertains to make and use the same.

The invention to be hereinafter described relates to automatic governor valves.

In order to more clearly disclose the construction, operation, and use of the invention, reference should be had to the accompanying drawings forming part of the present application.

Throughout the several figures of the drawings like reference characters designate the same parts.

In the drawings: Figure 1 is a central, vertical, cross section through an exhaust control valve; Fig. 2 is a like view through the governor valve; and Fig. 3 is a side view showing the two valves and their connections.

The main objects of the invention are to provide a simple, efficient, economical, durable, and compact governor valve adapted to automatically control the admission of exhaust to a heating system.

Referring to the drawings in detail, 1 indicates an exhaust valve casing provided with an inlet passage 2 leading from an engine or the like, an outlet 3 leading to the atmosphere, outlet 4 leading to a pipe 5 connected with a heating system, and a pressure inlet passage 6. Within the casing 1 is slidably mounted a piston 7 adapted to reciprocate in the lower part of the casing. A similar but smaller piston 8 is mounted to reciprocate in the upper portion of the casing and is normally maintained in its lowered position by a spring 9. The two pistons are connected by a piston rod 10 which carries a slide valve 11 adapted to close either the passage 3 or the passage 4, thereby diverting the exhaust either into the pipe 5 or into the atmosphere. A small bore 12 establishes communication between the passage 3 and the upper end of the casing to permit easy travel of piston 8. The passage 6, beneath piston 7 is connected to a pipe 13 provided with a small header 14 to

which are connected two short pipes 15 and 16 provided with plug valves 15' and 16', respectively. The opposite ends of these pipes are connected to steam passages 17 and 18, respectively, in the upper part of the body of the governor valve. To the opposite ends of these passages are connected pipes 19 and 20, respectively, provided with plug valves 19' and 20'. The opposite ends of these pipes 19 and 20 are connected to a small header 21 which, in turn, is connected to a pipe 22 leading from a boiler, air tank, or other suitable source of fluid pressure. The lower part of the body of the governor valve is provided with a diaphragm chamber 23 in which is mounted a diaphragm 24 on which rests the lower end of a small cylinder 25 slidably and reciprocably mounted in the body of the governor valve. The upper end is formed with a beveled valve face 26 to fit a corresponding valve seat 27 formed in the lower face of the partition between passages 17 and 18, and surrounding an inlet port therethrough. The stem 28 extends from the cylinder 25 upwardly through this passage and into a cylindrical member 29 and is provided with a cup 30 to receive the lower end of a spring 31 confined between it and a regulating screw 32, threaded into the upper end of the cylindrical member. The diaphragm chamber, below the diaphragm, is in communication with the heating system by means of a pipe 33 connected to the pipe 5. Now, assuming the parts to be in the positions of Fig. 3; when the pressure in the pipe 5 and connected heating system falls below the counter-acting force of spring 31, spring 31 will force member 25 down and open the port through the partition between passages 17 and 18. Pressure fluid will then flow from pipe 22 into header 21, thence through pipe 19 and passage 17, through the port in the separating partition and into passage 18, then into pipe 16, the header connected thereto, into and through pipe 13 and beneath piston 7 forcing it up and causing the slide valve to close outlet 3 and open outlet 4, so that the exhaust will pass into pipe 5 and into the system until the pressure therein has been raised to offset the action of spring 31, at which time the diaphragm will rise, closing the port through the partition. When this occurs, the pressure will be cut off from piston 7, of course, and the pressure fluid will escape

from beneath the piston, by means of a leakage duct 6^a in a plug 6^b threaded into the bottom of passage 6, thus permitting the slide valve to be moved back, by its spring, 5 to the position of Fig. 1. Any suitable form of check valve 100 is placed in pipe 5 between casing 1 and the connection with the system to prevent back pressure into casing 1, of course.

- 10 The operation of the invention has been described with reference to a low pressure medium for actuating the piston 7 and its co-operating parts. When a high pressure medium is used, the operation is exactly the 15 same, except that plug valves 19' and 16' are closed and plug valves 20' and 15' are opened, so that the high pressure medium flows in through pipe 20 and out through pipe 15. This arrangement for the high 20 pressure is to overcome the downward force which would be exerted by the high pressure medium in contact with the surface 26 while passing from passage 17 to passage 18, were the high pressure delivered by the pipe 19 25 and let off by pipe 16, as in the case of low pressure.

The invention is particularly adapted for a combination of air pressure, engine exhaust, and steam heating systems; as in the 30 case of train heating, for instance. In such case, the pipe 22 would be connected direct to the air reservoir, the casing 1 would receive the steam exhaust, and the heating system would be supplied with steam in the 35 usual manner.

It is thought that the construction, operation, and use of the invention will be clear from the preceding detailed description.

Changes may be made in the construction, 40 arrangement, and disposition of the several parts of the invention without in any way departing from the field and scope of the same, and it is meant to include all such within this application wherein only a preferred form has been disclosed.

Having thus fully described my invention, what I claim as new and desire to secure by Letters Patent is:

1. In combination; an exhaust receiving 50 casing having an inlet and two outlets, one of which outlets communicates with the atmosphere; a steam supply pipe communicating with the other outlet of the said casing; a check valve mounted therein; a governor 55 valve connected to a source of supply of

fluid pressure and adapted to have the direction of flow of the pressure fluid therethrough changed; means for changing the direction of flow of the pressure fluid through the said governor valve; connections between the said governor valve and steam supply pipe; a piston mounted in the said exhaust receiving casing; a slide valve operative thereby and adapted to close the lower outlet of the said casing when the piston is depressed and to close the upper outlet when the piston is raised; a pipe connected to the governor valve casing and to the exhaust receiving casing, beneath the said piston; and leakage means provided in the 60 said exhaust receiving casing beneath the 65 said piston.

2. In combination; an exhaust receiving casing having an inlet and two outlets, one of which outlets communicates with the atmosphere; a steam supply pipe communicating with the other outlet of the said casing; a check valve mounted therein; a piston mounted in the lower part of the said casing; a piston rod carried thereby; means 70 for normally holding the said piston in depressed condition; a slide valve carried by the said piston rod and adapted to close the lower outlet of the said casing when the piston is depressed, and to close the upper 75 outlet when the piston is raised; a governor valve casing provided with superposed communicating passages; a pipe communicating therewith and adapted to be connected to a source of fluid pressure; a second pipe communicating with the passages of the said 80 governor valve casing and with the said exhaust receiving casing, beneath the said piston; control means interposed in the said 85 pipes; a pipe connected to the said steam supply pipe and to the lower end of the said 90 governor valve casing; means for controlling communication between the passages of the 95 governor valve casing in accordance with the pressure in the last mentioned pipe; and a 100 plug communicating with the interior of the said exhaust receiving casing, beneath the said piston, and provided with a leakage duct.

In witness whereof I have hereunto set 105 my hand in the presence of two witnesses.

IRÉNÉ DEFOY.
